UNITED STATES PATENT OFFICE

164,047

FLUID TRACTOR

Ambrose Mazzola, South Gate, Calif., assignor to
Angelus Engineering Corporation, Maywood,
Calif., a corporation of California

Application October 31, 1949, Serial No. 5,799

Term of patent 14 years

(Cl. D41—1)

To all whom it may concern:

Be it known that I, Ambrose Mazzola, a citizen of the United States, residing at South Gate, in the county of Los Angeles, and State of California, have invented a new, original, and ornamental Design for a Fluid Tractor, of which the following is a specification, reference being had to the accompanying drawing, forming part thereof, in which:

Fig. 1 is a perspective view of a fluid tractor showing my new design;

Fig. 2 is a side elevational view thereof;

Fig. 3 is a top plan view thereof;

Fig. 4 is an end elevational view thereof; and

Fig. 5 is a bottom view thereof.

I claim:

The ornamental design for a fluid tractor, substantially as shown.

AMBROSE MAZZOLA.
